UNITED STATES PATENT OFFICE

MARCUS G. WRIGHT AND FRANCIS D. WOOTTON, OF DENVER, COLORADO, ASSIGNORS TO THE O. M. FRANKLIN BLACKLEY SERUM COMPANY, OF DENVER, COLORADO, A CORPORATION OF COLORADO

CORD SEVERING IMPLEMENT

Application filed April 7, 1932. Serial No. 603,762.

This invention relates to improvements in implements of the type usually referred to as emasculatomes of the type shown and described in United States Letters Patent No. 5 1,754,241, granted April 15, 1930.

The object of this invention is to produce an implement of the type mentioned which shall be so constructed that it will be very rigid and therefore reliable in its operation 10 and which shall also be so constructed that it can be readily disinfected and cleaned.

The general object of inventions of the type to which this improvement relates is to provide means for severing the spermatic 15 cord of animals and also for severing the umbilical cord at birth.

Instruments of the type referred to are so constructed that they will sever the spermatic cord without cutting the skin in which 20 it is enclosed so that this operation can be performed without cutting and subsequently without loss of blood.

In instruments of this type it is desirable to have the two jaws so mounted that when 25 they approach each other they form an oblique angle with each other in which the outer ends of the jaws are closer than the inner ends, thereby producing a gripping action that will hold the implement in place and 30 prevent it from accidentally slipping.

The above and other objects that may become apparent as this description proceeds are attained by means of a construction and 35 an arrangement of parts that will now be described in detail, and for this purpose reference will be had to the accompanying drawing in which the invention has been illustrated, and in which:

Fig. 1 is a side elevation of the implement showing the same in closed condition;

Fig. 2 is a side elevation similar to that shown in Fig. 1, but with the handles broken away and the jaws in open position;

Fig. 3 is a section taken on line 3—3, Fig. 45 1;

Fig. 4 is a section taken on line 4—4, Fig. 2; and

Fig. 5 is a section taken on line 5—5, Fig. 3, and shows the construction of the adjusting means.

In the drawing reference numeral 1 indicates a handle having a hand grip portion 2 and an arcuate portion 3 which is curved on the arc of a circle. A jaw member 4 is provided at the end of the arcuate portion and the side 5 of the jaw adjacent the arcuate portion coincides with a radius of the circle of which the arcuate portion forms a part. Although the edge 5 is preferably radial, it is not absolutely necessary that this should be so as the implement will function in substantially the same manner, even if this edge is inclined with respect to the radius in either direction, although such inclination must be somewhat limited.

A second jaw member 6 is provided with a curved edge 7 whose curvature is the same as that of the arcuate portion 3 and is adapted to fit against the latter. This jaw member has an edge 8 that is preferably radial 70 with respect to the curvature of the edge 7, but as explained in connection with the edge 5, edge 8 may vary from the radial to the same extent as edge 5. The second jaw is provided on each side with a groove 9 that 75 is concentric with the curved surface 7 and attached to the arcuate portion of the handle are lugs that have inwardly projecting portions 11 that extend into the groove 9 in the manner shown more clearly in Fig. 4. 80

The lugs 10 serve to hold the second jaw member in position adjacent the arcuate surface 3, but permits the jaw member to move with respect to the handle member. It will be apparent that if the curved surfaces 3 and 7 are arcs of circles and if the edges 5 and 8 are radial with respect to these surfaces, then when the second jaw member is moved along the curved surface 3, its motion will be the same as if it turned about a 90 pivot located at the center of the arcuate surface 3. From this it will be seen that when the two jaws are in the position shown in Fig. 1, the edges 5 and 8 are parallel, but if the jaw member 6 is moved away from jaw member 4, then the two edges 5 and 8 will become inclined to each other for the reason that they intersect at the center of the arc as above explained. For the purpose of moving the jaw member 6, a lever 12 has been 95 100

provided. This lever has a hand grip portion 13 and is provided with two parallel spaced portions 14 through which the handle part 1 extends in the manner shown on the drawing. The parts 14 are provided with curved slots 15 for the reception of a pivot pin 16 and extends through the handle 1. The ends of members 14 project forwardly and extend over opposite sides of the jaw 6 to which they are connected by means of a pivot pin 17.

Referring now more particularly to Figs. 1 and 2, it will be seen that when the handle 1 and the lever 12 are in the position shown in Fig. 1, the two jaw surfaces 5 and 8 are parallel with each other and spaced a short distance apart. It might be mentioned here that this instrument is not intended for cutting and therefore the jaws must always be adjusted so that they will not be brought into contact with each other because if this were done, it would sever the skin and flesh interposed between them. When the handle and lever are moved apart from each other towards the position shown in Fig. 2, the jaw 6 will be moved away from jaw 4, but will follow the curved surface 3. Since the pivot 17 moves in the arc of a circle whose center is at the intersection of the jaws 5 and 8 extended, it is evident the pivot 16 must move with respect to the lever portions 14 and in order to permit this movement, the slot 15 has been provided.

Slot 15 is so curved that when the jaws are brought to closed position against some resistance, then the pressure necessary will be between the convex side of the slot 15 and the pin 16 and by so forming this slot that a line drawn through the pivot 16 and through the pivot 17 when the jaws are in closed position, will pass through the center of curvature of the slot, then a construction is produced in which the leverage increases as the jaws approach each other and in which the jaws become practically locked when in the position shown in Fig. 1, from which it will be seen that with the parts adjusted in the manner described and shown any force tending to separate the jaws will not have any component tending to rotate the lever 12.

In order to permit the edges of the jaws to be properly adjusted so as to obtain the most desirable results, an adjusting means has been provided which has been illustrated in Fig. 5. From Fig. 5 it will be seen that the jaw member 6 is provided with an opening 18 in which is located a circular plug 19. Plug 19 is provided with an eccentric opening 20 through which the pivot pin 17 extends. It is evident that by turning the plug 19 in the hole 18, the relationship of the edge 8 of the jaw can be varied with respect to the pivot 17.

For the purpose of adjusting the plug 19 in the opening 18, jaw member 6 has been pro-

vided with two openings 21 that are preferably radial with respect to the opening 18 and located in each of these openings is a threaded plug or screw 22. These screws have conical ends 23. The plug 19 is provided with conical depressions 24 into which the conical ends 23 of the screws extend. In the form illustrated, the distance between the adjacent surfaces of the conical openings 24 is greater than the distance between the conical surfaces of the screws when the latter are in their innermost position, and therefore it is possible by moving one of the screws outwardly and the other inwardly, to effect a slight rotation of the plug 19, which is sufficient to effect the required adjustment of the edges 8 and 5 of the jaws.

From the above description it will be seen that the implement that forms the subject of this invention is of a rigid construction and so formed that the jaws as they approach each other are closer together at the outside than at the inside, whereby a clamping action is obtained that serves to hold the implement in place during the operation. It will also be seen that by means of the construction shown and described, the leverage is greatly increased as the jaws approach each other this increase in leverage being due to the straining of the toggle and also to the curvature of the slot 15.

It is also desired to call attention at this point to the fact that by removing the pivot pin 17 the jaw 6 can be removed for cleaning and it is therefore possible to maintain this instrument in an antiseptic or sterilized condition with less amount of labor and care than is necessary with instruments that cannot be so readily separated.

Particular attention is called to the fact that the two jaw surfaces 7 and 8 have a movement relative to each other, that is to say as if rotated relative to each other about the center of the arcuate surface 3.

Having described the invention what is claimed as new is:

1. A funis severing implement, comprising, a handle member having one end provided with a jaw, that part of the handle adjacent the jaw being curved on the arc of a circle, the side of the jaw adjacent the curved portion being substantially radial with respect to the arcuate surface, a second jaw member movably connected with the arcuate portion, said second jaw member having one side curved on the same radius as the arcuate portion of the handle, the side of the second jaw adjacent the first jaw having the same inclination with respect to its arcuate surface as the first jaw has with respect to the arcuate portion of the handle, means for slidably securing the second jaw to the arcuate portion of the handle, and means for moving the second jaw towards and away from the first jaw.

2. A funis severing implement comprising, a handle member having one end provided with a jaw, that portion of the handle adjacent the jaw being curved in the arc of a circle, the side of the jaw adjacent the curved portion of the handle being substantially radial with respect to the arcuate surface, a second jaw member movably connected with the arcuate portion of the handle, one side of the second jaw member being curved on the same radius as the arcuate portion of the handle, the side of the second jaw member adjacent the first jaw being substantially radial with respect to the curved surface, means for holding the second jaw member in contact with the arcuate surface of the handle, and means comprising a lever for moving the second jaw member along the arcuate surface of the handle towards and away from the first jaw member.

3. A funis severing implement comprising, a handle member having one end provided with a jaw, that portion of the handle adjacent the jaw being curved in the arc of a circle, the side of the jaw adjacent the curved portion of the handle being substantially radial with respect to the arcuate surface, a second jaw member movably connected with the arcuate portion of the handle, one side of the second jaw member being curved on the same radius as the arcuate portion of the handle, the side of the second jaw member adjacent the first jaw being substantially radial with respect to the curved surface, means for holding the second jaw member in contact with the arcuate surface of the handle, and a lever having one end pivotally connected with the second jaw member and having slideable pivotal connection with the handle.

4. A funis severing implement comprising, a handle member having one end provided with a jaw, that portion of the handle adjacent the jaw being curved in the arc of a circle, the side of the jaw adjacent the curved portion of the handle being substantially radial with respect to the arcuate surface, a second jaw member movably connected with the arcuate portion of the handle, one side of the second jaw member being curved on the same radius as the arcuate portion of the handle, the side of the second jaw member adjacent the first jaw being substantially radial with respect to the curved surface, means for holding the second jaw member in contact with the arcuate surface of the handle, means comprising a lever for moving the second jaw member along the arcuate surface of the handle towards and away from the first jaw member, means comprising a lever for moving the second jaw member towards and away from the first jaw, and means for increasing the leverage of the moving means as the jaws approach each other.

5. A funis severing implement comprising

ing, a handle member having one end provided with a jaw, that portion of the handle adjacent the jaw being curved in the arc of a circle, the side of the jaw adjacent the curved portion of the handle being substantially radial with respect to the arcuate surface, a second jaw member movably connected with the arcuate portion of the handle, one side of the second jaw member being curved on the same radius as the arcuate portion of the handle, the side of the second jaw member adjacent the first jaw being substantially radial with respect to the curved surface, means for holding the second jaw member in contact with the arcuate surface of the handle, and a lever having one end pivotally connected with the second jaw member, said lever crossing the handle, the handle being provided with a pivot pin and the lever having a curved slot through which the pivot pin extends, the curvature of the slot being such that the pressure between the pivot pin and the side of the slot is on the convex surface of the slot.

6. A funis severing implement comprising, a handle member having one end provided with a jaw, that portion of the handle adjacent the jaw being curved in the arc of a circle, the side of the jaw adjacent the curved portion of the handle being substantially radial with respect to the arcuate surface, a second jaw member movably connected with the arcuate portion of the handle, one side of the second jaw member being curved on the same radius as the arcuate portion of the handle, the side of the second jaw member adjacent the first jaw being substantially radial with respect to the curved surface, means for holding the second jaw member in contact with the arcuate surface of the handle, a lever having one end pivotally connected with the second jaw member and having slideable pivotal connections with the handle and means for effecting an adjustment of the second jaw member with respect to the lever.

7. A funis severing implement comprising, a handle member having one end provided with a jaw, that portion of the handle adjacent the jaw being curved in the arc of a circle, the side of the jaw adjacent the curved portion of the handle being substantially radial with respect to the arcuate surface, a second jaw member movably connected with the arcuate portion of the handle, one side of the second jaw member being curved on the same radius as the arcuate portion of the handle, the side of the second jaw member adjacent the first jaw being substantially radial with respect to the curved surface, means for holding the second jaw member in contact with the arcuate surface of the handle, a lever having one end pivotally connected with the second jaw member and having slideable pivotal connections with the han-

dle, and means for effecting an adjustment of the second jaw member with respect to the lever, said last named means comprising a cylindrical plug mounted in an opening in the jaw member, said plug having an eccentric opening for the reception of a pivot pin and means for turning the plug with respect to the jaw member.

In testimony whereof we affix our signatures.

CERTIFICATE OF CORRECTION.

Patent No. 1,877,376.

September 13, 1932.

MARCUS G. WRIGHT ET AL.

It is hereby certified that the name of the assignee in the above numbered patent was erroneously written and printed as "The O. M. Franklin Blackley Serum Company," whereas said name should have been written and printed as The O. M. Franklin Blackleg Serum Company, as shown by the records of the case in this office; and that the said Letters Patent should be read with this correction therein that the same may conform to the record of the case in the Patent Office.

Signed and sealed this 22nd day of November, A. D. 1932.

M. J. Moore,
Acting Commissioner of Patents.
